UNITED STATES PATENT OFFICE.

FREDERICK L. BICKEL, OF PHILADELPHIA, PENNSYLVANIA.

WASHING MACHINE.

Application filed June 13, 1923. Serial No. 645,162.

This invention relates to machines adapted for washing, bleaching, scouring, dyeing or otherwise treating fabrics and other materials, and it has reference more particularly to machines including means whereby the fabrics or materials under treatment are periodically compressed and relaxed so as to alternately expel and absorb the treating fluid or dye.

10 The primary object of this invention is to provide an improved machine of the foregoing referred to type characterized by certain novel features; to wit, means whereby the fabric being treated is engaged and 15 pushed forward during a portion of the operation, said means being capable of adjustment: means whereby an excess of oxygen may be supplied to the machine when it is desired to bleach the fabric or material 20 being treated; and means whereby pulsation of the treating liquor or dye is prevented and the articles under treatment more thoroughly saturated, thereby considerably increasing the efficiency of the machine.

25 In addition to the foregoing this invention comprehends improvements in the details of construction and arrangement of the correlated parts of what I now regard as the preferred embodiment of my invention from 30 among other possible forms and arrangements embraced within the spirit of said invention and the scope of the appended claims.

Briefly summarized, my present invention 35 consists of a vat or tub fitted with an oscillatory diaphragm adapted to periodically sweep the curved bottom thereof, said bottom including a perforate corrugated section that offers resistance to the material being moved 40 thereover whereby the greater amount of absorbed liquid is expelled at each successive active motion of the oscillatory diaphragm.

In the further disclosure of the invention reference is to be had to the accompanying 45 sheets of drawings illustrative of one practical embodiment wherein the features above outlined are incorporated, and in said drawings like characters of reference designate the same or corresponding parts in all the 50 views.

Fig. I is a sectional elevation of a washing machine illustrating my invention.

Fig. II is a cross-sectional view of the same; and,

55 Fig. III is a perspective view of a toe

piece or plate hereinafter more particularly described.

According to the form of my invention illustrated I construct a rectangular framework 4 conveniently of angle section material and comprising spaced verticals 5, 5 braced by upper and lower ties 6, 7 respectively; while each of the aforesaid verticals 5, 5 is fitted at its lower end with a swiveling 60 castor 8 or the like whereby movement in any desired lateral direction can be easily accomplished. The vat or tub 9 is constructed of non-corrodible sheet material, and, as best seen in Fig. II, its cross-sectional configuration is substantially that of a quadrant 65 bounded by end walls 10, 10, a curved bottom 11, terminating at the front of the machine above its vertical center, and a back wall 12 the lower part 13 whereof deflects outwardly 70 in a plane substantially parallel with a 75 radius through the aforesaid vertical center. This vat or tub 9 is conveniently strengthened and braced at its back wall 12 by a transverse reinforcement 14 whereby adequate support is afforded for the spigots 15, 15, as will be readily understood by those conversant with the art. The upper ends of the aforesaid back and end walls 12 and 10, respectively, as well as the upper frontal 80 part of the curved bottom 11 are transversely 85 extended to provide a rigid top 16 the perimetrical edges whereof are folded under at 17 and riveted or otherwise fixedly secured to the lateral flanges of the aforesaid upper 90 ties 6.

A removable cover 18 conveniently of sheet metal hollow construction—for the sake of lightness and rigidity—is adapted to seat by means of a perimetrical flange 19 in the open top of the vat or tub 9 whereby the machine 95 may be utilized as a table or support, and in order to ensure the necessary rigidity said tub or vat 9 is braced by a plurality of stay rods 20.

The curved bottom 11 of the vat or tub 9 100 is pocketed to provide a sub-division affording a by-pass 21 for a circulatory purpose, as will be more definitely explained later. The sub-division is effected partly by a corrugated sheet metal liner or false bottom 22 105 suitably spaced and supported by wooden bearers 23 from the curved bottom 11, and a correlated sheet metal liner or false bottom 24 likewise supported by wooden bearers 25 and it will be readily seen on an examination 110

of Figs. I and II that said false bottoms 22, 24 substantially close in that part of the curved bottom 11 established by the pocket or by-pass 21. The troughed channels of the 5 corrugated sheet metal liner or false bottom 22 are pierced by a series of drain apertures 26 as indicated in Fig. II.

In the course of the treating operation, as practised according to my invention, the 10 material under treatment is subjected to the action of an oscillating diaphragm 27, suspended by means of arms 28, from a rock shaft 29. This rock shaft 29 is journaled in the end walls 10 of the vat or tub 9 at a 15 point somewhat forward of the back wall 12, while it will be noted that when the diaphragm 27 is at its extreme inward position as best seen by Fig. II—that it is located in close juxtaposition and substantially parallel with the hereinbefore referred to inclined lower part 13 of the back wall 12, with the resulting formation of a divergent interspace 30 that functions to quell turbulence and splashing as later explained, as 20 well as affording a sufficient clearance for the spigots 15, 15.

During operation, the lower end of the oscillating diaphragm 27 arcuately sweeps very close to the false bottoms 24 and 22, as 25 well as the upper frontal part 31 of the curved bottom 11, a gradual but very slight progressive increase in the interval however taking place due to the eccentricity of the rock shaft 29, with respect to the center of curvature of said false bottoms 24 and 22, and curved frontal portion 31. Thus in 30 swinging upward to its normal limit of oscillation the outer end of the diaphragm 27 moves a little farther away relative to the 35 parts 22 and 31, so as to prevent the material treated being pinched between the end of said diaphragm and the corrugations in the part 22.

As a means for oscillating the diaphragm 40 27, I employ a self-contained mechanism which includes an electric motor 32 conveniently supported on a platform 33 transversely mounted in the lower part of the framework 4 on the ties or braces 7. This 45 motor 32 may be connected to any convenient source of electric energy in the well known way, and in turn it imparts motion through the medium of a belt 34—or other appropriate drive—to a pinion 35, in mesh with a gear 36 splined on one end of shaft 37 journaled in bearings 38 at the rear of the back wall 12 aforesaid. This shaft 37 is fitted at its other end with a crank member 39 in turn connected by means of a forked link 40 50 pivoted at 41 to the lower end of an arcuate arm 42, whereby the rotary motion of said crank is translated into and imparts oscillatory movement to the rock shaft 29. This arm 42 has its center of curvature coincident with the axis of rotation of the gear 55

36 when said arm is in the retracted position, and it will be readily understood that the amplitude of oscillation of the diaphragm 27 may be varied by adjusting the pivot 41 in the forked end of the link 40 according to the 60 requirements of the particular use to which the machine is to be put in practice. Furthermore by virtue of its curvature the arm 42 will always come to its limit of retracted movement in the position illustrated; and 65 it is desired, at this junction, to stress the fact that the arm 42 is of arcuate formation as clearly indicated by the line shading in Fig. I and as shown by dotted outline in Fig. II.

In connection with the oscillatory diaphragm 27 I provide an automatic material engaging and pushing means embracing an angled toe piece or plate 43 the lateral or operative portion 44 whereof is tessellated along its edge at 45 and formed with a rib 46 on its underside for a purpose hereafter explained. On the other hand the back portion 47 of the toe-piece or plate 43 is provided at its ends with pintles 48 supported by appropriate leaves or hinge members 49 conveniently attached to the diaphragm 27. In order that the toe piece or plate 43 may operate automatically it is influenced by a flat or leaf spring 50 which normally tends to maintain said plate in the position shown in Fig. II, while its engaging capacity is adjustable by means of a heel portion or lug 51 slidable through a slot 52 in the diaphragm 27 coating with the inclined end 53 of a slotted bar 54 guided by a screw or stud 55 and adjustable by means of a wing nut 56 on a screw threaded rod 57 in opposition to a compression spring 58.

The machine is also provided with auxiliaries such as a pivoted check valve 59 extending longitudinally of the vat or tub 9 and serviceable in controlling proper circulation of the heating fluid or dye, and an outlet 60 for drainage purposes, said outlet being provided with a suitable closure plug 61.

It is worthy of note that by limiting the extent of the corrugated false bottom or wash board 22 there is provided a smooth surface 31 over which the material or fabric slides after passing said corrugated false bottom when the machine is in operation and consequently it does not fall backwards out of engagement with the toe piece or plate 43. Furthermore it will be apparent that the toe piece or plate 43 being pivoted by the pintles 48 and normally held forward by the spring 50, when the diaphragm 27 swings forwards and upwards the tessellated edge 45 engages the fabric or material being treated and causes said plate to swing backwardly and grip the fabric while the rib 46 serves to push said fabric or material forwardly. It is also noteworthy that the heel or lug 51, operating through the diaphragm 130

27 by co-action with the end 53 of the slotted bar 54, functions to control the degree of friction imparted to the fabric or material being treated.

5 In operation as the diaphragm 27 moves through the active portion of its oscillation, in urging the material or fabric forward and upward, the level of the treating fluid rises at the front of said diaphragm and falls at the rear of the same, the resulting difference of head causing the displaced fluid to flow downwardly through the material and perforated false bottom 22. As the fluid drains through the material mass, the latter, by virtue of its own weight under saturation, settles upon the surface of the false bottom 22, thereby offering resistance to being moved by the diaphragm 27. As a consequence of this action the lower surface of the material will be gathered and compressed by the co-action of the tessellated edge 45 with the corrugations in said false bottom into a series of plaits, thereby expelling the greater amount of the absorbed 20 liquid, while the upper portion of said mass will remain saturated and comparatively relaxed. Notwithstanding the aforesaid resistive action of the false bottom 22, it is to be understood that the material mass 30 as a whole is nevertheless shifted to a considerable extent.

The return movement of the diaphragm 27 causes the fluid to rise quickly at the back thereof into the divergent interspace 30, the excess flowing through an intermediate 35 grilled part 64 of said diaphragm onto the material mass. This action results in the cascading of the treating fluid or dye in a series of streams over the material being 40 treated and it will so continue until a state of equilibrium of the fluid is established upon both sides of the diaphragm 27 whereby more thorough oxygenation, or aeration, is obtained. As the diaphragm 27 retracts, 45 the material mass does not roll back as might be expected, because the corrugated false bottom 22 prevents any movement of that portion with which it is in direct contact, and therefore, the greater bulk left in 50 a relaxed condition, as above noted, breaks or divides substantially at the center of the mass and fills the intervening gap. This latter action is assisted by the cascading of the fluid or dye through the grilled opening 55 64 in the diaphragm 27, as already described.

Furthermore, I have found that it is impossible to scour goods in a closed tub or vat, and that it is necessary to drive the fabrics or materials so treated out of the fluid so as to absorb air, while said fluid should pass through air and be aerated or charged with oxygen to ensure proper bleaching. In this attachment I fit a perforated connection or box 62 near the upper

front, which extends the full width of the vat or tub 9 and is adapted through the medium of a conduit 63 connected with a blower or vacuum pump—not shown—to maintain a suction of air over the surface of 70 said vat or tub whereby effective oxygenation or aeration of the fluid is maintained. When a blower is used it serves to extend the oxidation, and a vacuum is employed for extracting the water from the goods or for 75 aeration. In the latter case it may be found advantageous to provide an atmospheric air inlet for the tub or vat 9 and to seal the cover 18. For extracting the operation is as follows: the drain 60 is opened by elevation of the plug 61 while the tub or vat 9 is kept in motion, and as soon as said tub or vat is drained the vacuum pump is started thus exposing all surfaces of the goods 80 under treatment to the action of said vacuum, whereby the use of a centrifugal extractor is avoided.

On the other hand when dyeing materials in my machine the conditions above set forth are reversed; or, in other words, it 90 becomes necessary to squeeze the materials under the liquid so as to absorb the bath and not the air.

It is noteworthy that the backward inclination of the lower part 13 materially increases the efficiency of my machine as it ensures an effective cascading and constant circulation of the fluid through the material mass as will be perfectly obvious without further explanation.

From the foregoing, it will be seen that by the co-operation of the several associated elements, which constitute my invention, not only is the fluid caused to circulate through the material, but the position of the latter is continuously shifted and at the same time subjected to a compressive action, which ensures thorough permeation without causing any tangling and injury resulting directly therefrom.

Still further it is noteworthy that the aeration or oxidation of the material or fabric treated in my improved washing machine is accomplished as follows:

As the diaphragm 27 oscillates it causes the treating fluid to rise at the back thereof and cascade through the grilled interval 64 thereby effecting its proper aeration. In effect, the treating fluid is properly imbued with air while cascading through the grilled interval 64. This maintenance of the bath saturated with fresh air has for its object to prevent evaporation of oxygen from the water or fluid that is held in the material when articles are under bleaching treatment.

As the material or fabric moves out of the vat or tub 9 into the air in the turning and opening up process long enough to be cooled somewhat, the water or fluid in said mate-

rial or fabric acquires fresh air, and when the goods are returned into the bath of treating fluid, there will be a correlated increase in the quantity of oxygen. To increase the degree of oxidation fresh air can be admitted from outside the vat or tub through the inlet 62, and not being laden with moisture from the bath, and relatively cooler in temperature, will ensure better oxidation.

Obviously the invention is susceptible of minor detail changes without departing from its essential features, therefore the right is accordingly reserved to make such variations as fairly lie within the scope of the subjoined claims.

Having thus described my invention, I claim:

1. In a machine for treating fabrics comprising a receptacle for the treating fluid and an oscillatory diaphragm for periodically moving the fabric under treatment, the combination of a spring influenced angle-section member pivoted on the diaphragm and adapted to engage the fabric during progress out of and into the treating fluid.

2. In a machine for treating fabrics comprising a receptacle for the treating fluid and an oscillatory diaphragm for periodically moving the fabric under treatment, the combination of a spring influenced angle-section member pivoted on the diaphragm and adapted to engage the fabric during progress out of and into the treating fluid, and means for varying the travel of said member in one direction relative to the oscillatory diaphragm.

3. In a machine for treating fabrics comprising a receptacle for the treating fluid and an oscillatory diaphragm for periodically moving the fabric under treatment, the combination of a forwardly urged angle-section member pivoted on the oscillatory diaphragm and adapted to engage the fabric during progress out of and into the treating fluid, and means limiting the travel of said pivoted member in one direction whereby its influence may be varied.

4. In a machine for treating fabrics comprising a receptacle for the treating fluid and an oscillatory diaphragm for periodically moving the fabric under treatment, the combination of a forwardly urged angle-section member pivoted on said oscillatory diaphragm and having the free edge tessel-

lated, a longitudinal rib thereunder, a reversely directed heel on said member, and an adjustable stop for cooperation with said heel whereby the backward movement of the angle-section member may be varied.

5. In a machine for treating fabrics comprising a receptacle for the treating fluid and an oscillatory diaphragm for periodically moving the fabric under treatment, the combination of a spring influenced angle-section member pivoted on said oscillatory diaphragm and having the free edge tesselated, a longitudinal rib thereunder, a reversely directed heel on said member, and means for co-operation with said heel limiting the travel of the angle-section member in a rearward direction whereby its influence may be varied.

6. In a machine for treating fabrics, the combination of a tub for the treating fluid, said tub being of quadrangular cross-section with a concentrically spaced corrugated and perforated section medially thereof, an obtusely angled back in said tub, an oscillatory diaphragm having its end movable in close proximity to the tub bottom and being adapted to closely approach the angled portion of said back, a member having a tessellated edge pivotally mounted on the aforesaid diaphragm, means normally urging said member forwardly, and adjustable means limiting its movement in a reverse direction.

7. In a machine for treating fabrics, the combination of a tub for the treating fluid, said tub being of quadrangular cross-section with a concentrically spaced corrugated and perforated section medially thereof, an obtusely angled back in said tub, an oscillatory diaphragm having its end movable in close proximity to the tub bottom and being adapted to closely approach the angled portion of said back, an angled member having a tessellated edge pivotally mounted on the aforesaid diaphragm, means normally urging said angled member forwardly, adjustable means limiting its movement in a reverse direction, and means to maintain suction of air above the treating fluid so as to ensure effective aeration.

In testimony whereof, I have hereunto signed my name at Philadelphia, Pennsylvania, this 8th day of June, 1923.

FREDERICK L. BICKEL.
